UNITED STATES PATENT OFFICE

2,447,436

DISTANCE METER

Brice E. Sharp and George M. Hackman, Knoxville, Tenn.; said Hackman assignor to said Sharp

Application February 28, 1946, Serial No. 650,926

4 Claims. (Cl. 33—125)

1

Our invention relates to improvements in distance meters for measuring purposes in the performance of athletic stunts, and exercises, the primary object in view being to provide a simply constructed, inexpensive and accurate apparatus for measuring and giving a visible reading of distances accomplished in the performance of such stunts and exercises, and which will not injure one using the same, is quick acting and will not readily get out of order.

Other and subordinate objects, also comprehended by our invention, together with the precise nature of our improvements and the manifold advantages thereof, will be readily understood when the succeeding description and claims are read with reference to the drawings accompanying and forming part of this specification.

In said drawings:

Figure 1 is a view in front elevation of our invention in a preferred embodiment thereof,

Figure 2 is a view in plan.

Figure 3 is a view in vertical longitudinal section taken on the line 3—3 of Figure 2 and drawn to an enlarged scale,

Figure 4 is a view in vertical transverse section taken on the line 4—4 of Figure 3.

Figure 5 is a view in side elevation of the lever arm contracted,

Figure 6 is a fragmentary view in plan of the lever arm, partly broken away and shown in section,

Figure 7 is a detailed view of the over-rotation brake,

Figure 8 is a view in side elevation of the helmet and the safety connection thereon,

Figure 9 is a view in vertical section taken on the line 9—9 of Figure 8 and drawn to an enlarged scale,

Figure 10 is a view in front elevation of the height gauging plate, and

Figure 11 is a fragmentary view in vertical section taken on the line 11—11 of Figure 3 and drawn to an enlarged scale.

Reference being had to the drawings by numerals, our invention, as shown, comprises a base panel 1, of rectangular form, with a super-structure arising therefrom including corner legs 2 converging in pairs upwardly to a connector 3, the legs 2 preferably having the form of pipes, the feet 4 suitably connected to the base panel 1, the connector 3 having the form of a pipe coupling. A pair of front and rear uprights 5, 6 arise from opposite sides of the connector 3 in laterally spaced parallel relation with lower ends connected to said connector 3 by elbow couplings

7, 8 and a pair of upper and lower, vertically spaced horizontal rods 9, 10 connecting the upper end portions of the same. An upright, rod-like frame 11 extends equidistantly from opposite sides of the front upright 5 and is suitably secured thereto. A similar frame 12 similarly extends from the rear upright 6 opposite to and parallel with the frame 11. Cross rods 13 connect the frames 11, 12 at the corners thereof and at suitable points intermediate said corners.

10 The super-structure described in the foregoing supports operating parts now to be described.

A horizontally disposed lever arm 14 is pivotally mounted adjacent to what constitutes the 15 rear end thereof on the cross rod 9 for vertical swinging movement between the uprights 5, 6 and the frames 11, 12 and which is adapted to extend well beyond one side of said frames 11, 12. Preferably, the lever arm 14 comprises a 20 pair of side by side sections 15, 16, the latter slidably endwise on the former to extend or contract the overall length of the lever arm, as occasion may require, for instance when the meter is in use or not in use. For this purpose, the 25 section 15 is longitudinally slotted as at 17, and bolts 18, with wing nuts 19 thereon are extended through the slot 17 and the section 15 so that said section 15 may be set along the section 16 as desired.

30 The lever arm 14 is operatively connected adjacent the inner end thereof to one end of a pawl carrying beam 20 pivotally mounted intermediate its ends for vertical rocking movement between the uprights 5, 6 and on a horizontal 35 sleeve 21 journaled adjacent one end in a bearing 22 provided on the upright 5 intermediate the top and bottom of the frame 11. The operating connection between the lever arm 14 and pawl carrying beam 20 comprises a link 23 having the yoke ends 24, 25 pivoted to said arm and beam as at 26, 27.

The pawl carrying arm 20 has pivoted on the opposite ends thereof, as at 28, 29 a pair of oppositely disposed pawls 30, 31 spring pressed, as 45 at 32, 33 to engage a ratchet wheel 34 fixed on the sleeve 21 alongside said beam 20 by a collar 35 on the sleeve bolted to said wheel 34, as at 36. Suitable spacing collars 37, 38 are provided between the ratchet wheel 34 and pawl carrying beam 20 and between said beam and a bearing 39 on the upright 6 having a purpose presently seen.

An indicating sweep arm 40 is fixed by a set screw 41 on one end of the sleeve 21 and in front 55 of a dial disc 42 fixed, as at 43, to the upright

5 concentrically of the sleeve 21. The dial disc 40 is provided with a circular series of numbered 10 graduations 44 arranged in ascending order counter-clockwise as viewed from the front of the disc and starting from zero at the top of said disc. The series of graduations 44, as shown, are 15 designed to represent measurements in feet but may represent centimeter measurements if desired.

A pawl disabling beam 45 is pivotally mounted 20 intermediate its ends on the sleeve 21 for vertical rocking movement alongside the ratchet wheel 34, between said wheel and the upright 5, and is provided with a pair of arcuate end shoes 46 25 extending oppositely from the ends of the beam and circumferentially of said wheel 34 in spaced relation thereto. A set collar 47 on the sleeve 21 between said beam 45 and the hub 22 maintains 30 said beam 45 in proper relation to the ratchet wheel 34 and locks the sleeve 21 against end-wise creeping forwardly. At this point, it may be explained that to strengthen the sleeve 21, a shaft 48 is extended therethrough with one end keyed as at 49 in the bearing 39. As will be seen, the spacing collars 37, 38 and the pawl carrying beam 20 prevent the sleeve 21 from creeping rearwardly.

The pawl disabling means 45 is designed to be set into different angular positions to interpose the shoes 46 between the teeth of the ratchet wheel 34 and the pawls 30, 31, for a purpose presently seen. To this end, a stem 50 secured, as at 51, to said beam 45 extends from one end thereof and outwardly from between one side of the frames 11, 12 with its outer end projecting through a vertical slot 52 provided in a height indicating plate 53 suitably secured to appropriate cross rods 13, said plate being suitably graduated to indicate the height of persons operating the meter. A nut 54 on the stem 50 operative for clamping engagement with said plate 53 provides for maintaining the pawl disabling beam 45 in selected set positions.

Preferably the outer end of the lever arm 14 is provided with a depending operating bar formed of relatively slidible sections 55, 56 for extending or contracting the over-all length of said bar, as desired, said sections 55, 56 being slidably connected together by suitable clamps 57 and the section 55 being pivoted to said lever arm 14, as at 58. A suitable waist strap 59 is suitably connected to the lower end of the section 56 by a shackle 60.

In lieu of the described operating bar and waist strap 59, a helmet 61 may be used for operating said lever arm 14. The helmet 61 is adapted to be connected to the outer end of the lever arm 14 by means of a flexible short shaft section 62 having a clip 63 on one end for pivoting on said arm. At its other end, said shaft section 62 is provided with a yieldingly constructed clamp 64, of any suitable type, for engaging a stud 65 on the helmet 61 and forming with said stud 65 a pull-apart connection.

A friction brake is provided for the ratchet wheel 34 in the form of a spring pressed rod 66 slidably mounted in the upright 6 and provided with a friction head 67 for engaging one side of the ratchet wheel 34.

The described friction plate is for the purpose of preventing over rotation of the ratchet wheel 34 when operated by the pawls 30, 31.

The usual pivoted dog 68 tensioned by a suitably connected spring 69 is provided for preventing rotation of the ratchet wheel 34 in a

direction reverse to that in which it is designed to be operated by the pawls 30, 31.

The described invention is designed for use in operation in any kind of contest, or exercise, involving vertical body motion, or vertical limb motion, and especially jumping contests and exercises. It is not considered necessary to describe all the possible uses of the invention, the following example of its use being deemed sufficient for a proper understanding of the invention.

Describing now as an exemplifying use, and operation, of the invention, in vertical jumping, a person desiring to operate to measure a vertical jump is attached to the lever arm 14, with said arm substantially horizontal, either by the described lever arm operating bar and waist belt 59 or, by the helmet 61. The ratchet wheel 34 is rotated, by hand, counterclockwise, as viewed in Figures 1 and 5, to rotate the sleeve 21 similarly and effect swinging of the sweep arm 40 to indicate zero on the dial disc 42. The pawl disabling beam 45 is then set according to the height of the operator and by means of the stem 50 which is moved into registration with the proper graduation on the height gauging plate 53. In this operation, the shoes 46 are rotated in between the pawls 30, 31 and the ratchet wheel 34 so that the operator may stoop or bend, within a given range, before jumping and then straighten up before the pawls 30, 31 can engage the ratchet wheel 34. As the operator rises above his height the lever arm 14 is swung counterclockwise, the pawls 30, 31 caused to ride off the shoes 46 into engagement with the ratchet wheel 34 and to rotate said wheel counter-clockwise to thereby rotate the sweep arm 40 similarly and into registration with the proper graduation of the series 44 on the dial disc 42 so that the height of the jump is measured and a reading given. Obviously, when the operator descends, the pawls 30, 31 will ride over the ratchet wheel 34 idly and ride back onto the shoes 46.

When the helmet 61 is used, for instance in vertical jumping, the clamp 64 provides for releasing the helmet if the operator gets off balance, this being a safety provision.

The operating bars, 55, 56, and the waist strap or belt 59 may be used also in other exercises or contests involving vertical motion or limb motion, as will be clear.

The foregoing will, it is believed, suffice to impart a clear understanding of our invention, without further explanation.

Manifestly, the invention, as described, is susceptible of modification without departing from the inventive concept, and right is herein reserved to such modifications as fall within the scope of the appended claims.

We claim:

1. In apparatus of the class described, a dial disk graduated in units of measurement of successively increasing value, an indicator sweep arm operative over said disk around the axis thereof, a vertically rocking lever arm, means on one end of said lever arm for attaching the body of a person thereto for operation of said lever arm by jumping movement of said person, and means for operatively connecting the other end of said lever arm to said sweep arm comprising a ratchet wheel, and a rocking pawl carrying beam for rotating said wheel in one direction solely and to which said lever arm is operatively connected.

2. In apparatus of the class described, a dial disk graduated in units of measurement of suc-

cessively increasing value, an indicator sweep arm operative over said disk around the axis thereof, a vertically rocking lever arm, means on one end of said lever arm for attaching the body of a person thereto for operation of said lever arm by jumping movement of said person, means for operatively connecting the other end of said lever arm to said sweep arm including a pawl and ratchet drive, and settable means to disable the pawl and ratchet drive in accordance with the height of the person until said person has moved upwardly a distance greater than such height.

3. In apparatus of the class described, a dial disk graduated in units of measurement of successively increasing value, an indicator sweep arm operative over said disk around the axis thereof, a vertically rocking lever arm, means on one end of said lever arm for attaching the body of a person thereto for operation of said lever arm by jumping movement of said person, and means for operatively connecting the other end of said lever arm to said sweep arm comprising a ratchet wheel, and a rocking pawl carrying beam for rotating said wheel in one direction solely and to which said lever arm is operatively connected, and settable means to disable the pawls on said beam at will.

4. In apparatus of the class described, a dial disk graduated in units of measurement of successively increasing value, an indicator sweep

arm operative over said disk around the axis thereof, a vertically rocking lever arm, means on one end of said lever arm for attaching the body of a person thereto for operation of said lever arm by jumping movement of said person, and means for operatively connecting the other end of said lever arm to said sweep arm comprising a ratchet wheel, and a rocking pawl carrying beam for rotating said wheel in one direction solely and to which said lever arm is operatively connected, and settable means to disable the pawls on said beam at will comprising a rocking member having shoes thereon adapted to be interposed between the pawls on said beam and said ratchet wheel.
